WHEEL COVER

Moto Shimano, Los Angeles, Calif., assignor to Shore-Calvenar, Inc., Paramount, Calif., a corporation of California

Filed Apr. 15, 1960, Ser. No. 60,207

Term of patent 14 years

(Cl. D14—30)

Fig. 1 is a perspective view of a wheel cover showing my new design;

Fig. 2 is a front view of the wheel cover shown in Fig. 1; and

Fig. 3 is a cross-section taken along the line 3—3 of Fig. 2.

The fragmentary portion of the mounting ring shown in broken lines in Fig. 3 is for illustrative purposes only.

I claim:

The ornamental design for a wheel cover, substantially as shown and described.
